his Attorney

UNITED STATES PATENT OFFICE

TIBURCIO MARTINEZ, OF MEXICO, MEXICO

CARBURETOR

Application filed November 11, 1927, Serial No. 232,640, and in Mexico August 17, 1927.

My invention resides in improvements in carburetors. Its advantages are the following: First, to provide a standard carburetor for every class of internal combustion engines; second, a perfect and efficient action at any temperature, altitude or atmospheric pressure; third, the maximum economy with the maximum efficiency, avoiding excessive carbonization in the explosive chamber or 5 cylinders; fourth, facility in the starting of the engine, without requiring to flood it, and thereby wasting gasoline; fifth, ease in regulating the mixture without it being variable through vibration or other causes; sixth, an 10 easy adaptation of this system to any internal combustion engine, because a special carburetor can be constructed for each motor without changing the system.

I obtain these advantages with the parts 20 shown in the attached drawings, in which Figure 1 shows a sectional view of the system and of the parts of which it consists, and Figure 2 shows a sectional view of the same, partly in side elevation.

25 The following is a complete description of the system which I have invented, and of the parts thereof. The same letters refer to the same parts in the two figures.

Inside a special carburetor there is fitted a 30 choke tube "A", which I call "air regulator", which can be raised or lowered at will by means of a movable screw "D", which I call "atomizing control", which enters in the thread of the choke tube at its extreme left; 35 the movable screw "D" works within the bushing guide "F", attached in such a way to the carburetor as not to permit any decentralization of the movable screw "D"; in the lower part of the bushing guide "F" 40 there is attached a fastener "E" for the screw already described and which I call "stability fastener", and which has for its object that of preventing the screw "D" changing its position either through vibration or any other 45 cause, once it has been adjusted to the height desired; the screw "D" is worked at its end "I", by turning it by means of a bolt or lynchpin introduced in the hole in the end "I".

Precisely below the angular bushing "A" 50 there is a hollow mouth piece "B", which I

call "air saturator", and which is fixed to the walls of the carburetor and connected with the gasoline pipe "H"; in the upper and interior part of the mouth piece "B" there is screwed the gasoline nozzle "C", which I call 55 "gasoline feeder", and which is perforated at its lower part in order to permit the passage of the gasoline to the mouth piece "B" up to the highest level of the gasoline nozzle "C".

Upon raising or lowering the choke tube 60 "A" by means of the movable screw "D" any mixture of gasoline and air, from the richest to the poorest, can be brought about so as to produce a perfect gasification under all conditions, thus obtaining one of the advantages of my invention and as a consequence of this, the immediate starting of the engine is achieved, which is another of the advantages, and finally, there is obtained, by virtue of 65 the perfect gasification, a considerable economy in gasoline and less carbonization in the engine.

Once there is obtained, as is obtained by 70 my system, a perfect mixture of gasoline and air, as has already been stated, all the rest of the process and operation is carried out as in any other carburetor.

The mechanical system of my invention 75 will serve for any kind of special carburetor which may be constructed and which will be standard, inasmuch as it will serve for any internal combustion engine.

My system is exclusive because there does not exist a carburetor which is suitable for 80 any cylinder capacity without changing certain of its parts, whereas my invention can be adjusted by its own mechanism to any cylinder capacity, rectifying and correcting the pressure or temperature, a very important 85 factor for obtaining a perfect gasification, in order to secure the maximum of economy with the maximum of efficiency.

I claim as my invention the following:

1. In a carburetor, the combination of a 90 casing, having a mixing-chamber therein, a fuel supply nozzle arranged in said mixing-chamber and adapted to communicate with a source of fuel supply, a mouthpiece surrounding and enclosing the nozzle and com- 100

municating with the mixing-chamber only through the open outer end thereof, a choke tube slidably mounted in the casing above the open end of the nozzle and mouthpiece, and a screw threaded into said choke tube, longitudinally of the direction of adjustment thereof in the casing for adjusting said choke tube relative to the nozzle.

2. In a carburetor, the combination of a casing, having a mixing-chamber therein, a fuel supply nozzle arranged in said mixing-chamber and adapted to communicate with a source of fuel supply, a mouthpiece surrounding and enclosing the nozzle and communicating with the mixing-chamber only through the open outer end thereof, a choke tube slidably mounted in the casing above the open end of the nozzle and mouthpiece, and a screw threaded into said choke tube, longitudinally of the direction of adjustment thereof in the casing for adjusting said choke tube relative to the nozzle, a fixed bushing carried by the casing and in which the screw is journaled, and means normally tending to prevent the screw from turning in the bushing.

3. In a carburetor, the combination of a casing having a mixing chamber therein, a nozzle disposed in said mixing chamber, a choke tube slidably mounted above the nozzle, a screw threaded sleeve extending longitudinally from the choke tube, and a rod extending longitudinally beside the nozzle and threaded to said sleeve for adjusting the choke tube.

4. In a carburetor, the combination of a casing having a mixing chamber therein, a nozzle disposed in said mixing chamber, a choke tube slidably mounted above the nozzle, a screw threaded sleeve extending longitudinally from the choke tube, a rod extending longitudinally beside the nozzle and threaded to said sleeve for adjusting the choke tube, and a bushing mounted in the lower portion of the casing beneath the sleeve and in which the rod is journaled.

In testimony whereof he affixes his signature.

TIBURCIO MARTINEZ.
